UNITED STATES PATENT OFFICE.

OSBORN B. HALL, OF MALDEN, MASSACHUSETTS.

CASH-CONVEYER.

SPECIFICATION forming part of Letters Patent No. 293,012, dated February 5, 1884.

Application filed November 30, 1883. (No model.)

To all whom it may concern:

Be it known that I, OSBORN B. HALL, of Malden, in the county of Middlesex and State of Massachusetts, have invented a new and useful Improvement in Cash-Conveyers, which will, in connection with the accompanying drawing, be hereinafter fully described, and specifically defined in the appended claims.

This invention relates to devices whereby the selling-clerks in stores or other establishments are enabled to transmit with speed and certainty to the cash-accountant at a central office or station the money received from purchasing customers, and such accountant is enabled to return to each selling-clerk the change, if any, which is returnable to the customers; and the invention consists in the construction and combination of the divers devices embodied therein, as is hereinafter more particularly and fully set forth and claimed.

The accompanying drawing represents in elevation the devices which I employ, certain portions being shown in section, the better to illustrate interior parts.

In said drawing, A is a tube, which extends from the counter of the selling-clerk to the position or office of the cash-accountant. This tube is of such internal diameter as to furnish a conduit wherein a "cash-ball," which contains the money to be transmitted, will readily move by rolling by force of gravitation, by reason of the incline of the tube.

As a means of passing the cash-ball c into the inclined or upper portion of pipe A, a section, b, is arranged vertical and terminating at such height from the floor as the convenience of the operator may render expedient.

In the lower portion of section b, I arrange a plunger, d, provided with a handle, e, and a concave head, f, in which to seat ball c. Upon the lower end of the pipe is secured a screw-cap, g, through an opening in which plunger d plays freely. Between said cap g and head f is arranged a helical spring, a, which is compressed by drawing down the plunger, and which, by its expansive force, instantly raises the plunger to the admitted height, when it is liberated. An opening, h, is arranged in tube b, just above the normal position of head f, to enable the operator to

readily seat the cash-ball c in said head. At the junction of inclined pipe A and vertical part b the exterior line is swelled at i, to facilitate the passage of the cash-ball from a vertical to horizontal movement, until it shall have passed beyond a line projected vertically from and above point j, so as to insure the passage of the ball into inclined tube A, when projected, as will be stated.

In use the cash-ball c is placed in head f by passing it through opening h in tube b, when, by means of handle e, the operator depresses the plunger, the ball retaining its seat in head f as far as spring a will admit, when, by a sudden release of the handle, the plunger and ball are shot upward by the action of the spring, the plunger being arrested by its head, as shown, while the ball, following the exterior curvature of the pipe, passes into tube A, and by the incline thereof rolls on till it reaches the cash-accountant, when an opening, as at m, presents it to the attendant. I also arrange a whistle, k, in depending tube b, above head f, and in a convenient position for the operator, a cover, l, being hinged to tube b, and closed by a spring, so as to always close aperture h, unless opened for the insertion of the cash-ball, the same whistle being available for the operator at either end of the tube, and giving out its sound at the end of the tube opposite to where the air is forced in to operate it, said whistle being also arranged to serve as a speaking mouth-piece in the well-known manner.

B represents a tube inclined in an opposite direction to tube A, in order to return the cash-balls to the selling-clerk, an opening, n, being provided for the insertion of the balls, and a removable cap, p, at the opposite end for their arrest and removal.

By employing a tube as the conduit or path of the cash-ball, a speaking-tube is also provided without further loss of room; and, besides, goods of any kind may be packed closely against the tube without interrupting the movement of the ball; and by employing a depending tube, b, having a side passage for inserting the ball, and a plunger and actuating-spring for projecting the ball into the inclined tube A, space is economized and a compact and efficient elevator for the ball is provided.

I am aware that tubes have been employed in cash-conveyers wherein the cash ball or receptacle was actuated by an air-jet or exhaust; hence I do not claim tubes, broadly, for such conduits, my invention in behalf of tubes being confined to their use as an inclined conduit or way, through which the ball is impelled by gravity after being raised therein.

One chief merit of the use of a tube as an inclined conduit or way for the ball is the fact of its cheapness, as, unlike the tube in the pneumatic conveyer, it need not either be sufficient to resist the internal pressure of the air-blast, nor be air-tight even, all that is required being that it be of sufficient strength to sustain the ball and protect it from surrounding articles that may be placed next the tube.

I am fully aware of the United States Patent No. 282,893, granted August 7, 1883, and I claim nothing that is shown, described, or claimed therein, my invention differing therefrom in the several subject-matters which constitute the basis of my respective claims.

I claim as my invention—

1. In a cash-conveyer, the combination of an inclined guiding-way terminating in a depending section provided with an opening for the insertion of the cash-ball, a plunger arranged in said depending section, and provided with a head to receive said ball, a spring arranged to be depressed by the drawing down of said plunger, and adapted to elevate the same when released, and to thereby impel the ball into said inclined way, substantially as specified.

2. In a cash-conveyer, the combination of inclined conduit A, terminating in a depend-

ing section, b, having an aperture, h, for the insertion of the cash-ball, plunger d, provided with head f, to receive said ball, and also with a handle by which to depress it, and helical spring a, arranged to be depressed by the drawing down of said plunger, and when liberated to actuate the same, and thereby impel the ball into the inclined conduit, substantially as specified.

3. In a cash-conveyer embodying the inclined way A, terminating in depending section b, provided with devices whereby the cash-ball may be impelled from said depending section into the inclined way, an enlargement, i, in the outer angle or line of said way, at the intersection of the inclined and depending sections, whereby an enlarged radius of the curve is obtained, to facilitate the change of direction of the ball, substantially as specified.

4. In a cash-conveyer, the combination, with a tubular conduit for the cash-ball, of a whistle and speaking devices, whereby said tube may be utilized for transmitting oral messages, substantially as specified.

5. In a cash-conveyer, the combination, with suitable devices whereby the cash-ball may be elevated to the requisite height, of a tubular conduit arranged at an inclination to insure the traversing thereof by said ball by gravity alone when it has been elevated therein, substantially as specified.

OSBORN B. HALL.
